In Germany January 8, 1940

2 Claims. (Cl. 250—27.5)

The humming noise of electron tubes is caused by the electrodes vibrating under the influence of shocks and thus entailing current vibrations. In the case of directly heated tubes it is especially the thin filaments which easily vibrate like stretched chords and thereby produce a continuous tone, the attenuation at the ends of the filaments being low.

In order to overcome this disadvantage the practice has been, for instance, to support the middle of the filaments by insulating pieces, made of mica, for example, thus reducing the amplitude of the oscillation and improving attenuation.

According to the present invention, the filament is composed of two wires which are connected in parallel and are arranged to intersect and to bear against each other, as will be understood from the following description and the accompanying drawing, in which

Fig. 1 is a diagrammatic sectional view of a known filament, while Fig. 2 is a diagrammatic sectional view of an electron tube that comprises an example of filaments as provided by the invention.

The old arrangement, represented in Fig. 1, has a filament composed of two wires 1, 2 held in position by suitable supports 3, 4, as mica pieces, for instance, and connected in parallel to current leads 5, 6.

In the novel arrangement, Fig. 2, the wires 1, 2 of the filament are each supported from common leads 5, 6 and are so generally arcuately bent by means of the insulating supports 3, 4 that they intersect and bear against one another between these supports. As a result, longitudinal stretching is avoided and any vibration of the wires is readily stopped by the frictional contact between them and said supports which are evenly spaced

between the intersection of said wires and the junction point between leads and the ends of said wire. Said supports bowing the wires between their point of intersection and the junction point of said wires with the said leads.

What is claimed is:

1. An electron tube having in conjunction a filament comprising two wires which intersect and bear against each other having common supports for said wires at each end of said wires, each support carrying an end of both said wires and having insulating members spacing said wires at points intermediate the common points of support and the point of their intersection, said spacing members bow said wires into generally arcuate shape whereby said wires are rigidly supported without being stretched taut, and further whereby the possibility of vibrations being set up on said wires is minimized.

2. An electron tube having in combination a filament consisting of two wires which intersect and bear against each other midway between their common support which common support is located at each end of said wires each said support carrying an end of both said wires and having insulated members spacing said wires at points intermediate the common points of support and the point of their intersection, said spacing members bow said wires into an arcuate shape, and hold said wires rigidly without stretching said wires taut, said intersecting and bearing together of each of said wires in conjunction with their arcuation and the evenly spacing of said supports eliminate the possibility of vibrations being set up on said wires and reduce the amplitude of the oscillation of said wires and attenuation of said wires.

ALFRED GAEBEL.
